AUTOMATIC SUB- AND GRAND-TOTALING
MECHANISMWilliam W. Lasker, Brooklyn, N. Y., assignor to
Remington Rand Inc., Buffalo, N. Y., a cor-
poration of Delaware

Application February 11, 1933, Serial No. 656,233

11 Claims. (Cl. 235—61.7)

This invention relates to improvements in tabulating machines, and, more particularly, to the total taking mechanism thereof.

One object of this invention is to improve the total taking mechanism, so that the machine will automatically set instrumentalities for operation upon a change of designation, which may cause the machine to execute a plurality of total taking operations.

10 Another object of this invention is to improve the total taking mechanism, whereby a change of designation may cause the machine to take a single total, or a plurality of totals.

Another object of this invention is to improve 15 and simplify the change of designation mechanism for tabulators.

Another object of this invention is to construct an improved mechanism for retaining the reading as set by the sensing pin mechanism.

20 Another object of this invention is to construct a reading retaining mechanism, which may operate a change of designation mechanism from either a lower 90-column field, or from an upper 90-column field, when said fields are independent.

25 Another object of this invention is the elimination of many of these auxiliary mechanisms and the elimination of the use of special cards, which were heretofore necessary.

In the drawings:

30 Fig. 1 is a general diagrammatic view of the well known Powers tabulator.

Fig. 2 is a sectional view, with parts omitted, of a computing component, showing the paper handling mechanism, the printing mechanism, 35 and the slam bail mechanism, in conventionalized form.

Fig. 3 is a diagrammatic isometric view illustrating the picker mechanism, and its control.

40 Fig. 4 is a diagrammatic isometric view of the slam bail mechanism, and its control.

Fig. 5 is an isometric view of the forward totalizer wheels and the means for engaging and disengaging them with and from their actuators.

45 Fig. 6 is a diagrammatic view illustrating the timing mechanism of the rear totalizers, (just prior to the engagement of the rear totalizer wheels with their racks), and the connections between the total shafts, the slam bails, and the improved totaling mechanism.

50 Fig. 7 is a side view of the automatic sub and grand total taking mechanism, and its drive.

Fig. 8 is an isometric view (partly exploded) of the control mechanism for the rear totalizers.

55 Fig. 9 is a sectional view of the sensing mech-

anism, the reading retaining mechanism, and the change of designation device.

Fig. 10 is a view of a typical card.

Fig. 11 is an isometric view illustrating primarily the improvements in the reading retaining mechanism.

Fig. 12 is an enlarged isometric view of the change of designation tripping mechanism, and the reset mechanism for the total-control 10 clutches.

Fig. 13 is an isometric view of the grand total clutch locking and tripping mechanism.

Fig. 14 is a view similar to Fig. 13, of the sub total mechanism.

Fig. 15 is an exploded isometric view of the 15 cams, of the automatic sub and grand totaling mechanism, and the levers cooperating with said cams.

Fig. 16 is a sectional view of the totaling mechanism showing the cams for controlling the card 20 stop, the retract mechanism for the reading retaining mechanism, and the picker mechanism.

Fig. 17 is a view similar to Fig. 16, showing the cam for controlling total taking from the rear totalizers of the computing units.

Fig. 18 is a view similar to Fig. 16, showing the cams for controlling the slam bails.

Fig. 19 is a diagrammatic isometric view of the front total and grand total shafts, and some of their connections to the total taking mechanism, 30 and the zero stop control shaft.

Fig. 20 is an isometric view of the clutches and the sub total disabling link.

Fig. 21 is an isometric view of the grand total 35 disabling mechanism.

Fig. 22 is an isometric view of the subtotal reset and clutch disengagement mechanism.

Fig. 23 is a view similar to Fig. 22 of the grand total mechanism.

Fig. 24 is a view similar to Fig. 16, showing 40 the reset cams of the totaling mechanism.

Fig. 25 is a view similar to Fig. 16 showing the cams for controlling the taking of totals from the forward totalizers of the computing units.

Fig. 26 is a view similar to Fig. 16 showing 45 certain spline connections for the total cam shafts and a re-set device.

Fig. 27 is a top plan view of the dual total taking mechanism with indicia for locating detail sectional views.

50 Fig. 28 is an isometric view of the zero stop control mechanism.

General description

In order to give a better understanding of the

present invention, brief descriptions follow of various mechanisms which are well known in the tabulator art. These mechanisms, in some cases, are controlled, or have their operations timed from either of two cam assemblies, one of which is associated with the subtotaling mechanism, and the other with the grand totaltaking mechanism. These cam assemblies are in turn controlled or have their cycle of operation initiated by perforations in a card.

For the purpose of a systematic description, the well known Powers tabulator may be conceived as divided into three main components, viz: the base component 18 (Fig. 1), the intermediate component 17, and the computing component 16.

The base component contains the card hopper 1, the card feeding and picking mechanism 2, the sensing mechanism 3, the totaling mechanism 4, some of the main drive devices, the reading retaining mechanism, the change of designation mechanism, and a suitable framework for supporting the mentioned mechanisms. The framework is mounted on a leg supported bed plate (shown partially in Fig. 1).

The intermediate component consists of an open frame 6 for separating the base and computing components, and into which may be introduced any one of a variety of combinations of multiple translators.

The computing component contains the mechanism for summarizing and recording the items, or data, occurring as separate entries in pre-selected fields on the perforated cards. The computing component is ordinarily constructed with several computing units. A typical example of a computing unit is illustrated in section in Fig. 2.

Common or universal to all the computing units is a main drive mechanism (Fig. 1), the total shafts 7 and 8, a paper supporting platen, or carriage, with its paper feeding mechanism, ribbon feed devices (not shown), etc., the pertinent ones of which will be more fully described hereinafter.

The term "forward" herein means toward the front of the machine, which is towards the left in Fig. 1.

Framework

The machine, as a whole, is mounted on suitable legs attached to a main base plate (shown partially in Fig. 1), and on said base plate is a pair of boxlike frames 9, in which are housed the principal elements of the gearing, and the cams of the base component main driving mechanism. Mounted on the base 12 of the computing component is a series of intermediate frames for supporting the mechanism of the computing units. The said frames are tied together near the top with suitably located tie rods, which are used for the additional purpose of forming a pivot for the type carriers and actuators, and the universals connected therewith, which will be more fully described hereinafter. The end frames 6 carry auxiliary frames 13 for supporting the main rotation shaft 14, and for supporting the elements of the timing mechanism for the rear totalizers. Mounted near the forward upper ends of the frames 6 are the printing hammer assemblies, one for each computing unit.

Main drive

All the universal elements of the tabulator are connected to the main drive mechanism, which consists generally of a series of cam bearing shafts permanently geared together.

A suitable source of power, such as an electric

motor (not shown) is connected by a suitable form of clutch to the rotation shaft 160 (Fig. 1), on which is a series of worms for driving the base main shaft 52, the totaling mechanism main shaft 161 (see also Fig. 15), and intermediate shaft 5 for the computing component. Said shaft 160 is connected through suitable gearing to the card feeding rolls, as has been set forth in detail in my patent No. 2,044,119, dated June 16, 1936. The base mechanism main shaft 52 carries a pair of eccentrics for reciprocating the sensing mechanism 3, (Figs. 1 and 9) and a suitable set of cams for operating other universal mechanisms, as is fully set forth in the cited patent. The intermediate shaft 5 is geared to the computing head rotation shaft 14 (Fig. 1) which is provided with discs, which are in effect cranks, at each end, which are connected by pitmans (not shown) to arms fixed to the forward oscillating shaft 19 in the computing component. The shaft 14 carries a cam for rocking the zero stop control mechanism by means of shaft 124 (Fig. 2). Other ramifications of the main drive mechanism in the computing component will be noticed under the heading "Computing units."

Computing units

For each computing unit there is a fan cam 20 resiliently connected to the said oscillating shaft 19 (as shown in Fig. 2). Pivoted to each fan cam 20 is an irregular link 23, extending upwardly and rearwardly to one arm 23' of a frame 21, one side of which appears at Fig. 2 so that the said frame and fan cam always move together. One arm of the frame 21 is provided with a cam 21' in which fits a roller carried by a stud 22' rigid with the restoring frame 22. The lower ends of the arms of each restoring frame 22 are connected by a universal bar 22a for controlling the movements of the type carriers and actuating racks. Extending forwardly from the rear of the link 23 is an adjustable link 24, whose forward end is pivoted to a crank fixed to the shaft 25. Also fast to the shaft 25 is a universal hammer restoring bail (not shown) for each computing unit.

Near the base of the computing unit is a stop basket (Fig. 2) in which the stops 26 are located. The stop basket is substantially of the form shown in the patent to Lasker No. 1,780,621, dated Nov. 4, 1930. Therefore, an abridged description will suffice. Each stop is adapted to be elevated by an individual interpreter 27 to limit the movement of the totalizer actuators 28. There are three varieties of stops. The first variety represents the odd digits except 9, which is represented by the second variety exemplified by stop 29. When a stop 26 is elevated, the sector 28 is limited in its forward movement, an extent determined by an odd digit, but, if the stop 29 is also elevated, the pressure of the actuating spring of the sector 28 can force the projected stop 26 forwardly an extra space, so that each stop 26 may be used for determining the next higher consecutive even digit. The third variety of stop 30 is known as the zero stop. It is normally urged upwardly by a spring 31 connected to a bell crank 31 which in turn, has a zero stop 30 pivoted at 31a thereto.

Each computing unit is provided with the usual denominational series of spring urged totalizer actuators 28 to each of which is connected a type carrier 62 by the usual spring and pin-in-slot arrangement. The extent of movement of the actuators is governed by the de-

scribed stops 26, 29 and 30 for correspondingly controlling the extents of actuation of the totalizers. Associated with each type carrier 62 is the usual familiar printing hammer mechanism.

Some computing units are provided with two totalizers. In this case, a second actuator 171 for totalizer 34 is connected to the first mentioned actuator 28 as is diagrammatically shown 10 in Figs. 1 and 6.

All totalizer actuators 28 are provided with a spring and pin-in-slot connection with the corresponding type carrier 62 for effecting transfers or carrying of tens as is well known in the 15 art. One well known form of transfer is partially illustrated in Fig. 2.

This mechanism comprises a series of flat members 173, pivoted at one end on a stationary rod 173a. The opposite end of each of said 20 members is formed into a hook 173b as indicated by dotted lines in Fig. 2. The hooks lie between the totalizer wheels and the ends thereof serve as rear stops for sectors 28, the arrangement being such that a stud 28b on said 25 sectors contacts with the end of said hook limiting the sector's movement toward the rear. Each wheel in the totalizer, engaged by actuator 28, is provided with a tooth of substantially double thickness, the thicker section having a flat face 30 which engages once each revolution of a cam on the underside of the member 173 which stops the adjacent sector 28 of the next higher order, raising the nose of hook, permitting the sector 28 to move backward sufficiently to advance the 35 totalizer wheel engaged thereby one tooth, thus registering one complete revolution of the wheel of the lower order. This mechanism is old and it is believed that a more detailed explanation of the same would be superfluous.

40 Zero stops

Fixed to the rotation shaft 14 of the head of the machine is a cam 166, with which cooperates a roller on the arm 163 loose on the auxiliary grand total shaft 164. The said arm 163 is provided with a pair of gear teeth, which mesh with cooperating teeth on an arm 167 (Fig. 28) fixed to the auxiliary subtotal shaft 124. Also fixed to the shaft 124 is a series of arms 168, upon which lie pins fixed to one side of the frame 33. There is a frame 33 for each and every computing unit (or for each split portion of a computing unit). The forward end of the frame 33 is provided with a universal bar 33a for rocking spring urged bell cranks 31, to which the zero stops 30 are connected, by a spring and pin-in-slot connection. It, therefore, follows that, when cam 166 rocks arm 163, the shaft 124 and all of the frames 33 will be rocked to 50 positively rock the bell crank 31 and, through the spring and pin-in-slot connection, pull all the zero stops 30 to an ineffective position.

If shaft 124 is held in the position to which it has been rocked by cam 166, the frames 33 55 will be correspondingly held and all the zero stops 30 will be held retracted. With the continued rotation of shaft 14 it is obvious that cam 166 will move out of engagement with the follower 163. In order to retain the zero stops 60 in disabled condition after this has occurred, the following arrangement has been provided. Overlying the universal bar of the frames 33 of those frames associated with computing units provided with a grand totalizer, there is an arm 70 75 169 fixed to the auxiliary grand total shaft 164

(Fig. 28). Therefore, if the said shaft 164 is rocked while shaft 124 is held by cam 166, those frames 33, associated with grand totalizers, will be held in rocked position and, hence, the corresponding zero stops held depressed even after 5 cam 166 permits shaft 124 to rock.

The usual forward totalizing wheels 34 (Fig. 5) are rotatably mounted on a shaft 34a carried by a cradle (not shown), which is rocked by a pair of integrally connected cam arms 35 embracing the said shaft. This mechanism, generally speaking, is old. Pivoted to one of the arms 35 is a doubly notched pitman 36, which, when the mechanism is in adding adjustment, has its upper notch 36a in engagement with the 10 upper of a pair of pins on the rocker 37, the pins being on opposite sides of the pivot of the rocker, which, in turn, is fixed to its supporting shaft 37c, and said shaft is, in its turn, rocked through a biased wiper pawl assembly 38 by the 15 periphery of the fan cam 20. The wiper pawl 38 is actuated shortly after the fan cam 20 rocks from its rest position to lower the totalizer out of engagement with its actuators 28, and shortly after the said cam 20 begins its return excursion, 20 the wiper pawl 38 is again rocked to elevate the totalizer into engagement with the actuators. It is thus seen that the wheels 34 are lowered out of engagement with their actuators 28 (Figs. 1 and 2) near the beginning of the cycle, 30 so that said actuators can assume positions determined by the stop basket, and raised into engagement with the actuator near the mid point of the cycle to register or accumulate the extent of movement of the said actuators. This 35 is the usual adding timing of the forward totalizers.

If the pitman 36 (Fig. 5) is lowered so that the lower notch 37b thereon can be engaged by the 40 lower pin on the rocker 37, it is obvious that the engaging and disengaging movements of the wheels 34 are exactly opposite that described in the preceding paragraph, for the first rocking movement of the arm 37 is ineffective and merely results in permitting notch 37b of the pitman 45 36 to engage the lower pin of said rocker and the second rocking movement lowers or disengages the totalizer from its actuators. This is the total timing. Each pitman 36 is connected by a slotted link 175 and spring 176 to a bell crank 39, loosely pivoted on the sub-total shaft 8, and the horizontal arm of each bell crank is resiliently urged upwardly by a suitable spring 39a so that the upper notch 36a of the pitman 36 normally engages the upper pin of the rocker 37. When the 50 bell crank 39 is rocked its fullest extent, as it is by the shaft 8 when set for a sub-total the pitman 36 is drawn downwardly, but the lower notch 37b may not engage the lower pin because the totalizer is usually, (always after a series of additions), in engagement with its actuators, therefore, the lower pin of the rocker supports the pitman in an abnormal position, as shown in Fig. 5, until after the fan cam 20 has shifted the 55 rocker 37 and then the lower notch of the pitman engages the lower pin of the rocker in the manner described in the first sentence of this paragraph. An exactly similar action occurs in the first adding cycle after a total cycle. The 60 bell crank 39 is rocked by either of the total shafts 7 or 8 as described under "Total links."

The distance between the pins on the rocker 37 is such that the pitman 36 may have an intermediate position and, hence, not be in oper- 75

ative engagement with either of the pins as shown in Fig. 5.

If the totalizer wheels 34 are disengaged from their actuators at the beginning of the cycle, and 5 remain disengaged throughout the cycle the totalizer timing is that of a non-add operation; the wheels 34 receive no movement from the actuators 28 and, hence, nothing is accumulated. Each pitman is provided, at its forward end (see 10 Fig. 5) with a pin 177 as a part of one means for shifting said pitman to its intermediate position.

Totalizer timing (rear)

15 Each forward totalizer has its individual timing and control mechanism, but all rear totalizers have the principal part of their timing mechanism in common. The rotation shaft 14 (Figs. 1, 2 and 8) has fixed thereto a cam 40 (Fig. 6). 20 Behind one of the crank discs 40a and cooperating with said cam 40 is a pair of spring connected bell cranks 41 and 41a (a partially exploded view of the mechanism being shown in Fig. 8) one of which always acts on the pitman 42, which 25 is pivoted to an arm 119 fast to the shaft 43. The shaft 43 has fixed thereon an arm 44 which is resiliently connected by spring 46 to a bell crank totalizer cradle 45 (Figs. 1 and 8), which carries the rear totalizing wheels in such a manner that, when a bell crank 41 or 41a, which 30 happens to engage the pitman 42, is rocked by the cam 40 on shaft 14, the arm 44 ascends to raise and disengage the totalizer wheels 34' from their actuating racks 171. When the bell crank 35 rides off the high part of the cam 40, the sets of totalizer wheels 34' are brought into engagement with their racks by the strong spring 120 (Fig. 8) acting on crank 178. The upper of the bell cranks 41a is the total-taking crank and the other 41 (or lower) is the adding crank. The 40 arrangement is such that the adding bell crank positively rocks the totalizers 34' out of engagement with their racks 171 at the beginning of the cycle and permits the spring urged arm 45 to re- 45 engage the totalizer wheels 34' with their racks 171 near the mid-point of the cycle. If the upper bell crank 41a engages the pitman 42 the order of operation will be the reverse of that just described and, hence, the totalizer wheels 34' 50 will be cleared or reset.

If the pitman 42 is engaged by the adding bell crank 41a and the latch 48 is biased to engaging position by a forward movement of the link 49 which is joined to the latch 48 by a usual 55 form of spring and pin-in-slot connection, the shaft 43 will not be permitted to rock when the adding bell crank 41 passes off the high part of its actuating cam, hence, the totalizing wheels 34' will remain out of mesh during the entire cycle 60 and, therefore, a non-add timing is the result.

Base

A stack of pre-grouped cards 50 (Fig. 1) is first inserted in the magazine, 1. During the regular 65 operation of the machine the cards are ejected seriatim from the magazine, are then sensed and individually tabulated. The cards are extracted from the stack by a picker knife 51 driven, through a link lever mechanism, by a cam on the rotatable 70 main shaft 52. The shaft 52 makes one rotation for each card tabulated; each rotation is designated a cycle. Fixed to the shaft 52 (Fig. 3) is a cam 96, whose periphery rocks an arm 97, through roller 98, to move the notched link 99, which, 75 through arm 100, and spring 100b secured thereto

rocks shaft 101, which, in turn, through an arm and link, operates the picker 51. The picker 51 feeds the card to the pair of feed rollers 53 arranged to transport the card rearwardly into the sensing chamber 55b and against a normally 5 effectively positioned card stop 55. The sensing chamber is located between a sensing pin box 75 (Fig. 9) and an interponent pin box 57, and consists of a pair of matched perforated plates having a perforation for every possible perforation 10 of the card. While the card is in the sensing chamber, the sensing pin box 75 is moved upwardly by a pair of links 58 (Fig. 1) embracing eccentrics 58a fast to the main shaft 52. The pin box 75 is provided with sensing pins 59 arranged in columns and corresponding to all possible perforations in the cards and in the matched plates of the sensing chamber there being twelve such rows in the present embodiment. If there is no hole in the card being sensed, the pins 59 15 are held back when they strike the card. If there is a hole in line with any one or more of the sensing pins 59, then that pin (or pins) is not arrested by the card and, due to the movement of the sensing box 75, its spring will cause it to 20 pass through the perforation in the card as shown in the case of the single pin 59 illustrated in Fig. 1. Just before the pins, which pass through the perforations in the card, strike the lower ends of the interponent pins 54 of the reading retaining 25 device (shown in Fig. 11), they will be locked in stationary positions relative to the pin box 75 by the series of cam controlled locking slides 60. When the box 75 is in its lower position, the slides 60 are held in ineffective position. Said 30 slides 60 are connected to a spring-pressed universal bail, which travels with the sensing pin box 75. Operatively connected with said bail is an arm 56, which extends downwardly and the lower end of which rides on a fixed cam 61. Continued upward movement of the pin box 75 results in positively elevating the interponents 54 and the corresponding wires in the translating device (Fig. 1) to set the corresponding stops 26 and variable block 29 (Fig. 2) for determining 35 the extent of movement of the actuator 28 and the type carriers 62. At about the time that box 75 has reached its highest position, the interponents 54 are locked in their raised positions by means of spring-pressed locking slides 63 cooperating 40 with pins 54a on the interponents 54. Said members 54 may be released as an incident to the sensing pin adjustment of other of the interponents 54. There are two of these locking slides 63 for each vertical row of pins, and displaced similarly to the slides 65 and 66, as plainly shown in 45 Figs. 9 and 11. One slide 63 has locking noses, only for the rear six pins 54, and the other only for the forward six pins. When the pin box 75 has receded downwardly far enough for the pins 59 to clear the sensed card, stationary cam 61 (Fig. 1) operates the slides 60 to release the locked sensing pins. Just after the sensing pins 59 have been released, the card stop 55 (indicated diagrammatically in Fig. 1) is retracted and the 55 skid rolls (not shown) in the sensing chamber feed the sensed card to the pair of ejecting rolls 64, thence into the storage magazine.

Change of designation

The means for sensing a change of designation (see Figs. 9, 11, 13, and 14) consists of two slideable grid bars 65 and 66, both slides being located on the same side of each vertical row of interponent pins 54. Said slide 65 has cam projec- 70 75

tions 67 in the six rear slots, which are operable by pins 68 in the pins 54, and are under control of the upper 90 column field. The slide 66, directly behind the slide 65, has cam projections 67a in the forward 6 slots and cooperates with pin 68, and is under control of the lower 90 column field (Fig. 11). The construction is such that either an upward or downward movement of a pin 54 will shift the proper grid bar and set the totaling mechanism, corresponding to said grid bar, into operation.

Extending between two supporting frames 69 are four comb bars 70 (Fig. 9), which are crenelated to act as guides and supports for the change of designation keys 72, which are arranged in echelon formation on four levels to facilitate the manipulation of said keys 72. Each key 72 is pivotally connected to an interponent 73 and is vertically adjustable to three positions being held in any of said three positions by the action of notches 72a and leaf spring combs 72b.

In the upper position of a key 72, its pivotally connected interponent 73 is above the path of travel of its corresponding grid bar, hence no action is transmitted to the totaling mechanism.

If a key 72 is in the second or intermediate position, the end 73b of its interponent 73 (Fig. 14) becomes interposed between the corresponding grid bar and the sub-totaling bail 74. With the relative parts in this position, the action of any of the pins 68 on any cam 67 will cause the tripping of the sub-totaling mechanism.

If the key 72 (Fig. 13) is in its lowermost position the end 73b of the interponent 73 will be interposed between the corresponding grid bar 65 and sub-totaling bail 74, while the heel 73a formed by the wide part of interponent 73 lies directly back of grand total bail 91, consequently, if the grid bar should be moved due to the action of pins 68 engaging cams 67 or 67a on the grid bars 65 or 66, both bails 74 and 91 will be moved to the left, resulting in the tripping of both sub and grand total taking mechanism. In the usual construction of the machine a slide 65 and 66 is provided for each column, bails 74 and 91 being of sufficient length so as to be operable from any of the desired columns.

The mechanism for tripping the sub and grand totaling bails 74 and 91 has just been described. Each of these bails, when tripped, sets in operation a train of mechanism which will be described further on under the heading of "Tripping mechanism". Before beginning this description, a summary of certain mechanical operations prerequisite to the operation of the total taking mechanisms will be given under the heading of "Total taking mechanism".

Two keys 72 and their interponents 73 are provided for each vertical row of index positions of the cards, one for cooperation with the grid slide 65 and the other for cooperation with the grid slide 66. Hereinafter the upper and lower halves of each such row will be called, respectively, the upper and lower columns, each row consisting of two columns.

Total taking mechanism

To obtain a total, the picker 51 (Fig. 1) must be blocked and held blocked to prevent any new cards from entering the sensing chamber during the spacing and total taking operations; the card stop 55 (Figs. 1 and 11) must be held closed to prevent the card, which initiated the totaling operation, from leaving the sensing chamber; the retract slides 63 must be disabled and held dis-

abled so that the cams thereon are not engaged by pins or studs 54a on pins 54; the machine must then operate through an idle operation to restore the tripped transfers (if any); and the machine must execute a single or a double total taking cycle, depending on the result required by the initiating designation change—a single cycle for a sub total or a double cycle for a grand total; after which the machine is finally restored to normal for continuing accumulating operations.

Tripping mechanism

Sub-total initiating bail 74 is supported at each end by arms 78 (Figs. 11 and 14) depending from a rockable shaft 76 supported by suitable bearings in frames 69, said arms 78 being situated within frames 69, consequently the left-hand arm 78 is not shown in Fig. 11.

Secured near one end of shaft 76 is a member shaped somewhat like a bell crank, the longer end 154 thereof normally engages a step 79c on a latch member 79b, which serves by means of a step or hook 79 formed at the lower end of arm 79a cooperating with spring 77 to retain a lever 80a secured to shaft 80b on which are fixed a pair of arms 80c and 80d, which control the operation of clutch 80.

Referring now to Fig. 14, it will be seen that when an interponent 73 is positioned by its key 72 so that the section 73b lies between the corresponding grid bar 65 or 66 and sub-totaling bail 74, the movement of the grid bar will be communicated to bail 74, which will rock shaft 76 causing arm 154 to lift step 79c, of arm 79b, withdrawing hook 79 from beneath lever 80a, permitting said lever and its shaft and also the clutch arms 80c and 80d carried thereby, to rotate in a clockwise direction under the influence of spring means 92 which will be described shortly.

Vertical shaft 161, by means of a worm 161a (Fig. 15), drives a unitary idler assembly comprising gear 83c in mesh with 161a, and a collar integral therewith provided, in the present embodiment with three equally spaced slots or recesses 83. This assembly is free to turn on a sleeve 83d, parts of which are shown in Figs. 15 and 27, and forms the driving side of a clutch.

Grooved disc 80 at one end of shaft 81 which rotates freely in sleeve 83d forms part of the driven side of said clutch.

Secured at the opposite end of 81 is a sleeve 82 integral with an arm having a slot 82a, in which a pin 133a, extending from cam 133, may reciprocate. One end of a compression spring 92 thrust over shaft 81 and seated in a counter-bore in sleeve 82 presses against 82, while the other end presses against sleeve 83d (Fig. 27) of the cam assembly. It should be noted that the cams shown in Fig. 15 are riveted together with the usual spacers between them (not shown) forming a unitary structure. Spring 92 presses outwardly on sleeve 82, which being fast on shaft 81 exerts similar pressure on disc 80 tending to rotate the arms 80c and 80d engaging the rim 65 in the groove thereof in a clockwise direction, but this movement is prevented as explained earlier in this section by the hook 79 on latch 79b until latch 79 has been released by the rocking of sub-total bail 74 by a grid bar 65 or 66.

When the clutch member 80 is released spring 92 draws said member into a position whereby a pin 180, carried by 80, enters one of three equally spaced grooves 83, thus connecting 80, shaft 81, member 82 to the totaling mechanism main shaft 75

161 through a set of gears of such ratio that the cam assembly makes a single rotation for three of the main shaft. At the time of a total taking operation, card picking is stopped, the card stop 5 is locked down, all zero stops disabled, and also the grand total mechanism must be locked during sub-total taking and, conversely, the sub-total must be locked during grand total taking.

When the sub-total mechanism is tripped and 10 its cam assembly has revolved to a point where cam 84a permits the roller 85 to drop to its lowest dwell, the lower end of the bell crank 85a, which carries the roller 85 (Figs. 15 and 21), takes a position over the step 86 (Figs. 12 and 15 21) of the grand total operating bell crank 87, thereby rendering the grand total taking mechanism inoperative. The sub-total taking mechanism is free to trip at any time and become effective, except when the grand total has been 20 tripped.

For a grand total tripping operation, a train of mechanism similar in many respects to that described in connection with the sub-total tripping operation is utilized. Since these mechanisms cooperate in their respective functions, it is thought advisable to include a description of the grand total mechanism at this point.

Referring to Figs. 9 and 11, a pair of arms 90 depending from a rockable shaft 88, supported by 30 suitable bearings in frames 69, one of said frames being shown in Fig. 11, support, at their ends, a grand totaling bail 91, said bail being situated above and somewhat to one side of bail 74. When a key 72 is in its lowermost position the interponent 73 pivoted thereto lies between the corresponding grid 65 or 66 and bails 74 and 91. The heel 73a of the interponent 73 lies in front of bail 91 and the lowermost section 73b is positioned between the end of a grid 65 or 66 and 40 sub-total bail 74. When said grid is actuated due to the engagement of cams 67 or 67a by a pin 68, the endwise movement of the grid occasioned thereby will press the interponent against both bails 74 and 91 rocking both shafts 76 and 88 which support the respective bails. Referring 45 now to Fig. 13, shaft 88 has secured thereto a bell crank shaped member, the longer arm 157 of which normally rests against the step 89c on one arm 89b of a pivoted latch member having 50 a second arm 158 spaced from the arm 89b. A spring 89 tends to rotate the latch assembly in a clockwise direction, but a stop is provided which limits the movement thereof so that the hook 158a at the end of arm 158 rests normally in a 55 position to prevent the counter-clockwise movement of an arm 87 (due to spring 93, Fig. 27) fast on one end of a shaft 87a having at its opposite end a slotted arm 87b (see Fig. 12), said slot engaging a pin in arm 87c secured to shaft 60 87d having arms 87e and 87f provided with pins 95a and 95b which ride in a groove in the periphery wheel or disc 95 forming part of a clutch mechanism generally similar to clutch 80 previously described. It should be noted here that 65 the joint between arms 87b and 87c reverses the motion of shaft 87a so that disc 95 tends to draw arms 87e and 87f in the same direction as the corresponding parts of clutch 80 are stressed by spring 82.

70 Furthermore, when shaft 88 is rocked due to the actuation of bail 91 arm 157 rises turning latch 89b in a counter-clockwise direction against the tension of spring 89 releasing the hooked end of arm 87 and permitting the hook to pass over hook 158a formed at the end of arm 158, thus

permitting a limited counter-clockwise movement of arm 87 which is communicated to clutch 95 by the train of mechanism just described.

Clutch 95 comprises a hub 83a fast with a gear 83b, driven by worm 161a on the shaft 151; 10 said gear 83b, making one rotation in four machine cycles. The difference in the diameters of gears 83c and 83b can be seen in Fig. 27. The cams 140, 112b, 84b, 116 and 137 are joined in a 15 unitary structure on sleeve 83e, the cam assembly being connected spline fashion to shaft 95a integral with wheel 95, by means of pin 131a projecting from the cam 137 into a slot in a collar 93b which is fastened to shaft 95a. A compression spring 93 surrounding shaft 95a is located between said collar and the end of fixed sleeve 83c and operates in the same manner as spring 92 described in connection with clutch 80. Spring 93 tends to draw the driven member 95 into engagement with the driving member 20 83a.

The driven member 95 has a pin 95b extending from its inner face which when the driven member is released by the actuation of grand total bail 91, enters one of four equally spaced 25 holes in the driving member 83a, causing the cam assembly to rotate.

When the grand total taking mechanism is tripped, the mechanism for causing the engagement of both clutches 80 and 95 is released. It 30 is necessary then to prevent the operation of clutch 80. Spring 93 is considerably stronger than spring 92, so when both clutches are tripped an arm 94 supported by a pivot 94a (Fig. 7) having at one end a pin 94b positioned to engage 35 the inner face of 80, while the opposite end of said arm is provided with a pin 94c which rides in a groove in the periphery of 95. The action of this mechanism is such that when both clutches are released, the stronger spring 93 causes the 40 engagement of the driving and driven members of the clutch 95, causing the rocking of arm 94 on pivot 94a resulting in pin 94b engaging the face of clutch 80, thus holding the driving and driven members of this clutch apart and preventing the operation thereof, thereby disabling the sub-total taking mechanism.

As may be seen in Fig. 15, both cam assemblies are driven but in opposite directions by a common worm, which, in turn, is continuously driven 50 from the main shaft 160. Each of the cam assemblies (best shown in Fig. 27), of the described totaling mechanisms governs certain mechanisms which will now be described in detail. The cam assemblies rotate at different speeds as above described and as may be seen by reference to Fig. 27.

Picker control

The picker 51 must be blocked against operation during a total taking cycle. When either 60 of the rollers 106 or 106a is lifted by its cam 84 or 84b arm 107a will be rotated in a clockwise direction. A link 182 connects arms 107a to an arm 183 secured to shaft 102 (Figs. 3 and 16). An arm 103 on shaft 102 is connected to an arm 185 fastened to shaft 186 by a link 184, provided with a slot 184a in which rides a pin 185a on arm 185. A spring 186b, secured to arm 185, tends to rotate shaft 186 in a clockwise direction. 65

Fixed to shaft 186 is an arm or pawl provided with a hook 104 which normally is positioned above and out of engagement with a link 99 provided with a notch 99a which connects arms 97 and 100, parts of the picker mechanism which 70 75

are reciprocated by means of spring 100b, cam 96 and roller 98 (see Fig. 3).

Referring to Fig. 16, when arm 107a rotates in a clockwise direction due to rollers 106 or 106a riding upon the elevated portions of their respective cams, this motion is transmitted by the train of mechanism just described to link 184, Fig. 3, and due to the action of spring 186b shaft 186 rotates in a clockwise direction until 104 rests on link 99 in position to drop into notch 99a in order to lock arms 97 and 100 of the picker mechanism just as roller 98 arrives at the highest part of cam 96, consequently preventing the feeding of a new card during the total taking cycle. The picker will remain locked as long as either roller 106 or 106a remains on the high spot of its cam, that is, until the blank and taking total cycles are complete.

Card stop control

The card stop 55 is operated by mechanism provided according to French Patent No. 739,656, Aug. 28, 1931, which mechanism is substantially that of my copending application S. N. 538,429, filed May 19, 1931, now Patent No. 2,044,119, and comprises the elements indicated by reference numerals 25, 262, 261, 257, 255, 254, 252, 251, 250, 247, 248, and 256, shown in Fig. 21 of said patent, the shaft 25 of the said patent being the same as shaft 52 of the present application. The rotation of shaft 52 then causes the counter-clockwise rotation of the shaft 109 (Figs. 9 and 11) and arms 55a which then force the card stop 55 downward at an appropriate time, against the tension of a pair of springs (not shown) which are located near each end and directly behind the card stop.

The card which initiates the total taking cycle must be held in the sensing chamber until after it has been properly sensed for an accumulating operation.

When either cam 84 or 84b raises its roller 106 or 106a (Figs. 15 and 16) the arm 108 of crank 107 engages the arm 109a on shaft 109 rocking the same in a counter-clockwise direction, against the tension of suitable springs (not shown) and it will be seen on examining Fig. 9, in connection with Fig. 11, that this will result in the counter-clockwise rotation of arm 55a on shaft 109, the end of said arm engaging card stop 55 forcing it downward so that it blocks the passage from card chamber 55b (Fig. 9).

Retractor

The pins 54 (Fig. 9) must be unlatched and remain unlatched during the blank and total taking cycles. When either cam 84 (Figs. 15 and 16) raises its roller 106, crank 107 is rocked and, through a link 182 and an arm 183 connected by slot 182a and pin 183a the shaft 102 is rocked. Carried by shaft 102 is a pair of arms 110 (Figs. 9, and 11) to the lower ends of which is fixed a universal retract bar 111, which extends across the rearward extensions of the spring pressed locking slides 63 (Fig. 9), hence, the cams 84 will hold all locking bars 63 in an inoperative or ineffective position. The retract bar 111 is normally actuated by an open cam on the main shaft 52 (not shown) and, when a totaling mechanism is tripped, the appropriate cam 84 of the cam assembly merely rocks the arm 107 to catch the bar 111 in retract position and hold it there irrespective of the position of the said cam on the main shaft 52.

Total links

When either of the total cams 112 or 112a (Figs. 15, 19, 25 and 27) actuates its corresponding roller 113 or 113a, the arm 114 is rocked and the link 115 is pulled downwardly, thereby rocking the front sub-total shaft 8 (Fig. 19) in a clockwise direction, and the rear sub-total shaft 124 in a counter-clockwise direction. These shafts 8 and 124 have been in use in Powers tabulators for many years and are shown in a number of patents, beginning with that to Powers No. 1,236,481, dated August 14, 1917. It will be seen in Figs. 2 and 6 that shafts 7 and 8 are situated in the forward part of the machine. When the said sub-total shaft 8 is rocked, the arm 117, affixed thereto, is rocked also in a clockwise direction and moves the link 118 rearwardly or towards the right of the machine, as shown in Fig. 19. The rearward end of the link 118 is pivotally connected to one end of a centrally pivoted rocker arm 188, the other end of which is resiliently connected to a link 49, which is drawn forwardly in reverse direction to link 118 by the rearward action of the link 118. By referring to Figs. 6 and 8 it will be seen that link 49 by means of spring 49a and slot 49b is connected to pin 48a in latch or hook 48, said hook being associated with other mechanism for controlling the engaging and disengaging of rear totalizer 34' with their racks 171, which will be described in detail further on.

The grand total taking mechanism disables the zero stops 30 in the following manner:—When grand total cam 116 lifts its cam roller 121b on arm 121a, the arm 121 (Fig. 17) is rocked by pin 121c elevating the end of 121 in contact therewith and thus pulling downward link 122 pivoted to the outer end of 121 (Figs. 1, 6, 15, 17 and 19). The downward movement of link 122 causes the rocking of grand total shaft 7 in a clockwise direction. A crank arm 123a on shaft 7 under these conditions causes link 123, pivoted thereto, to move to the right or rearwardly as is clearly shown in Fig. 19.

Slot 123b in the rear end of link 123 fits over a pin 164a in arm 164b secured to shaft 164. Referring now to Fig. 28, it will be seen that arm 169 on shaft 164, when rocked counter-clockwise engages bail 33a pressing it against spring urged bell cranks 31 (see Fig. 2) to which zero stops 30 are connected, forcing said stops downward to an ineffective position during the reverse turning of the totalizer wheels. The zero stop mechanism is more fully described earlier in this specification.

The rear totalizer cradles 45 are connected by link and spring with arms 44 fast on a rock-shaft 43, which is urged counter-clockwise by a strong spring 120 tending to draw the wheels 34' down into engagement with their racks. The shaft 43 is positively rocked clockwise to disengage the wheels, through an arm 119 of said shaft and a link 42 having a pin 422, which, by rocking said link, may be engaged alternatively with shoulders on a lower bell-crank 41 and an upper bell-crank 41a. Said bell-cranks carry follower rollers for co-action with a segmental cam 40 fast on the inner face of the disc 40a on the drive shaft 14. This cam is so disposed that it acts on bell-crank 41 during the first half and on bell-crank 41a during the last half of each cycle. For addition, the pin 422 is engaged with bell-crank 41a as shown in Fig. 8, and said bell-crank disengages the wheels in the first half cycle and allows them to re-engage in the last half. The link has 75

a spring, tending to swing it up into engagement with the total-taking bell-crank 41a. The link is normally held down as shown, by an arm 47 fast on the rear grand total shaft 164, said arm bearing on an extension 421 of the pin 422. When said grand total shaft is rocked counter-clockwise, the arm 47 moves upward and the pin 422 moves into engagement with bell-crank 41a. This allows the wheels to remain in mesh during the 10 first half and draws them out during the last half of the cycle. This mechanism is substantially like that of my prior application, Serial No. 535,842, filed May 8, 1931 and the corresponding French Patent No. 719,524; but in that machine 15 sub-totals were taken from the rear and grand totals from the front totalizers. The arm corresponding to the arm 47 was, therefore, mounted on the sub-total shaft corresponding to the present shaft 124, and the link, corresponding to link 20 49, was operated by the grand total shaft corresponding to shaft 164, so as to set the rear totalizers for non-add.

In the first part of the grand total cycle the grand total shaft 7 (Fig. 19) must change the 25 normal timing of the sub-totalizers to non-add in order to clear the machine. Fixed to the said grand total shaft 7 is an arm 127 for each computing unit provided with a grand totalizer, and, when said grand total shaft is rocked, each 30 arm 127 engages the corresponding bell crank 39 rockably supported by shaft 8 of the sub totalizer timing mechanism which is rocked sufficiently thereby to draw the pitman 36 by means of link 175 and spring 176 attached to arm 39, to an intermediate or non-add position, as was explained under "timing" (Fig. 5). This immediately follows a sub-total cycle at the end of which the totalizers 34 were left standing out of engagement with their racks.

40 When the sub total link 115 is drawn downwardly by cam 112a of the sub-total cam assembly (Fig. 25), the sub total shaft 8 connected thereto is rocked in a clockwise direction to reverse the timing of the sub total accumulators, 34, so that they will yield their totals. It is necessary to change the timing of the grand totalizer 34' to non-add. This is effected by a link 118 connected to a bell crank 117 fixed to the total shaft 8 (Fig. 19). Movement of the link 118 toward the right in Fig. 19 rocks a reversing lever 188 in a counter-clockwise direction and draws the link 49 forwardly towards the left (Figs. 8 and 19). Link 49 is connected to hook 48 by a spring 49a and pin 48a in slot 49b, thus spring biasing the hook 48. It will be remembered that the grand totalizers 34' are, early in the cycle, disengaged from their racks 171 by the action of cam 40 on the add bell-crank 41, which pulls the arm 119 forwardly, where, in a 45 sub-total cycle, it is caught by the spring-biased hook 48 which thus retains the grand totalizers in disengaged (non-add) position throughout the cycle. In order to hold all zero stops disabled during this totalizing operation a link (not 50 shown) similar to link 123 is connected by an arm to shaft 8 and the play in the slot at the rear end of the link is absorbed by the rocking of shaft 8, whereby the normal rocking of shaft 124 is prevented when the zero disabling cam 55 166 on the rotation shaft 14 passes off the roller of the arm 163 pivoted on the shaft 164.

Slam bails

When the totalizers of either set are disengaged from their actuating racks at the end of 75

the first half cycle of a total cycle, the corresponding actuators 28 (Fig. 2) are then ready to slam to the extreme of their movement under the stress in their tension springs. Machines containing 45 or more actuating sectors are likely to be noisy during totaling. In order to eliminate this objection, slam balls are used. Mechanism for this purpose is well known in the tabulator art, as shown by the following patents: 707,309, August 19, 1901 to Ellis et al.; 10 1,028,162, June 4, 1912 to Vincent et al.; 1,338,904, April 13, 1920 to Hopkins; 1,817,451, August 4, 1931 to Gubelmann; and 1,859,848, January 31, 1933 to Gubelmann. Since this mechanism is only incidental to the understanding of the 15 present invention it will be only briefly described. The slam balls 128 (one set is shown in Fig. 4) consist of a series of spring pressed intermediate stops (one for each actuator) so that, when the totalizer is disengaged the actuators can "slam" 20 only a short distance, irrespective of their adjustments when the set of totalizers is disengaged. The form illustrated has three intermediate stops 129 which may be interposed into the paths of the rearwardly extending actuating 25 spring hook, 130 of the actuators 28, (Figs. 1, 2 and 4). The pivoted slam balls 128 are interposed into the paths of the actuating spring hook 130 by rocking shaft 131, to which are fastened a series of bails 132 (only one shown 30 in Fig. 4) which are, in turn, connected to a set of slam balls 128 by short springs (best shown in Fig. 4). The slam balls are rocked into operating position at about the time that printing hammers are released, that is, at about the extreme end of the first half of the total cycle 35 of the computing mechanism.

The total taking mechanism must rock the shaft 131 at the proper instant. When the sub total taking mechanism functions, the cam 133 40 (Fig. 18) rocks an arm fixed to shaft 134 and draws link 136 downwardly, thus (Fig. 1) rocking the said shaft 131 to throw the slam balls 128 into effective position. When the grand total taking mechanism is functioning, the slam balls 128 are actuated by the same link 136 through cam 137 and the mechanism shown in Fig. 18. The grand total slam bail cam 137 has two rises, which operate the slam bails twice during one 45 grand total operation, for such operation requires a sub total then a grand total and the slam bails must be actuated each time that the totalizers are disengaged. The slam bails 128 are restored to their normal position by the action of spring 138 (Fig. 4), when the actuating cam 133 (or 137) allows its corresponding roller to 50 return to its low dwell.

The details of the slam bails are similar to those disclosed in the Lasker application S. N. 64,969, filed Feb. 20, 1936, in which shaft 206 60 corresponds to shaft 131 of the present application, bail 209 corresponds to the present bail 132, pawls 205 correspond to the present pawls 129 and link 212 corresponds to line 136.

Clutch disengagement and resetting of total mechanism

On the completion of a total taking cycle it is necessary to disengage the driving and driven members of the clutch which has been operated 70 by either of the totaling mechanisms. It is also necessary to reset the shaft 88 or 76 so that the arms 157 or 154 thereon are again restored to a normal position under their latches 89c or 79c, in order that the machine may resume its 75

normal tabulating operation. After taking a sub-total, this is accomplished as follows: Cams 139 and 140 are shown in their normal position in Fig. 24. It will be seen that roller 240 will follow a concentric surface of the cam 139 for almost an entire revolution before being engaged by the high part of the cam which will result in the partial rotation of the arm 145 to which it is attached; 145 being rotated in a clockwise direction together with shaft 144 on which it is mounted, said shaft turning in suitable bearings in a web or casting integral with housing 4, omitted in the drawings for the sake of clarity. On the opposite side of said frame an irregularly shaped arm 143 having a bent over lug of approximately square cross-section serving as a spring post as well as a retaining means for a latch, and a flattened section which serves as a support for a pair of pawls 146 and 147, pawl 146 being rotatably mounted on a stud 143a secured to arm 143, a spacer (not shown) being positioned on said stud between 146 and 143 to make room for the second pawl or latch 147 pivoted to the inner face of pawl 146 by pivot 146a, as shown in Fig. 24. Spring 146b tends to rotate both pawls in a clockwise direction, while spring 148 tends to rotate pawl 147 on its pivot 146a in a counter-clockwise direction in respect to pawl 146. On the upper edge of pawl 147 a step is cut forming a projection or nose 141, Fig. 22, said step being formed so as to pass under 142 so that 141 engages the side of 142, thus locking pawl 146 against clockwise rotation. The object of this mechanism will perhaps be more clearly understood from the following:

Just before the end of each sub-total taking cycle, as previously stated arm 145 and shaft 144 are rocked in a clockwise direction by cam 139. Cam 139 is so shaped that the roller 240, on arm 145, restores in the reverse direction after the sub-total taking cycle ends.

The pawl assembly is shown in normal unlatched position in Fig. 24. With the rotation of arm 145 the nose of pawl 146 engages a pin 150c (Fig. 7) in the frame of the machine, and as the rotation of arm 145 continues the end of said pawl is forced upward in respect to arm 143 against the tension of spring 146b, so that by the time arm 145 is rocked to its maximum extent the step 141 on pawl 147 which is pivoted to 146 rests under 142 with said step resting against 142. This holds pawl 146 rigidly against clockwise rotation.

A spring 152, attached to 145, which is stretched when roller 240 is on the elevated part of cam 139, is stronger than 92, and so when roller 240 drops from the high part of the cam to the normal position shown in Fig. 24, spring 152 rotates arm 145, shaft 144, arm 143, and the pawl assembly carried thereby in a counter-clockwise direction, and pawl 146 engages the under side of arm 151 separating the driving and driven parts of clutch 80, thus stopping the rotation of the sub-total cam assembly (Fig. 27). Arm 80a is again latched by hook 79, and crank 153 (Fig. 26) engages arms 157a and/or 154b on shafts 88 or 76 returning said shafts to their normal positions this when 145 is rocked down by the cam.

Pawls 146 and 147 are tripped to the position shown in Fig. 24, by a pin 150 extending from the frame. Said pin is engaged by an arm 149 at the end of 147 and the counter-clockwise rotation of arm 143 causes pawl 147 to rotate on its pivot 146a in a clockwise direction in respect to

arm 143, thus disengaging the step and nose 141 from the stop 142.

A similar mechanism is employed for de-clutching clutch 95. In this case arm 155 provided with a roller or cam follower 241, normally rests in the position shown in Fig. 24. When a grand total is taken, shafts 88 and 76 are rocked, and clutch 80 is disabled as previously explained, and arm 87 is unlatched by the rocking of shaft 88, permitting the counter-clockwise rotation of shaft 87a (Fig. 13) and the engaging of clutch 95.

Arm 156a is lowered when the clutch engages, and a pawl assembly similar to that just described in connection with the sub-totaling clutch actuated by spring 155a restores the clutch to its normal disengaged position and latches arm 87 again behind latch arm 158.

A pin 156 in arm 155a of 155 engages arm 145a causing it to rock in a clockwise direction resetting the balls 74 and 91.

On completion of the series of operations just described, the tabulator is ready to resume its accumulating operations.

Summarizing the operation of the machine, in a listing cycle both the front and rear racks engage on the return stroke with the respective accumulators. When the change of designation causes the operation of the sub-total mechanism, the front totalizers are engaged on the forward stroke and are disengaged on the return stroke. During the sub-total operation the rear totalizer remains at non-add. When a grand-total is taken, the rear totalizer goes in mesh on the forward stroke and on its return it is disengaged from the accumulators. During the grand-total operation the front accumulators remain at non-add.

The operation of taking a grand total is as follows: When on the sensing of a card a change of designation is detected in a grand total column, one of the slides 65 or 66 is vibrated, the motion being communicated by pendent 73 and ball bars 74 and 91 to the rock shafts 76 and 88. These (Fig. 12) by their arms 154 and 157 trip the two latches 79a and 158, releasing the two arms 80a and 87, resulting in releasing the rock shafts 80b and 87d so that the clutches on the two cam shafts are free to be closed. Since the spring 93 is stronger than the spring 92 (Fig. 26) and both cannot yield on account of the lever 94, the grand total spring 93 prevails and this clutch is thrown in setting the shaft 95a into rotation. The first effect (Fig. 16) is to rock the lever 107a and thereby to rock the two shafts 102 and 109. The rocking of shaft 102 and its ball bar 111 presses all of the lock slides 63 to inactive positive (Fig. 9); and also (Fig. 3) allows the pawl 104 to drop down on to the link 99 ready to lock said link as soon as it reaches its retract position, and thus to prevent the feeding of any more cards. The rocking of shaft 109 (Fig. 11) depresses the card stop 55 and retains the new card (the first card of the new group) in the sensing chamber. As will be apparent from the outline of the cams in Fig. 16, these parts will be held in the described positions for three-quarters of a turn of the cam 84b, that is to say, throughout three cycles of the machine. Nothing further occurs in the total control mechanism during the first quarter turn of the cam shaft, that is to say, during the first cycle, which is, therefore, a blank cycle resulting in the resetting of any operated transfer devices. The sensing pins come up through the card and the sector stops rise but, as they are not locked up by the

slides 63, they recede and the zero stops resume active position before the sectors are released; so that nothing is added or printed.

- During the second quarter turn of the cam shaft, that is to say, during the second cycle, the cam 112a (Fig. 25) oscillates levers 114a and 114, pulling the link 115 which (Fig. 19) rocks the group total shaft 8 and takes a total from the front totalizers in the manner common in the Powers tabulator. At about the middle of this cycle, the cam 116 (Fig. 17) rocks levers 121a and 121 and pulls the grand total shaft 1 (Fig. 19) by the link 122. This cam holds this shaft pulled until the end of the third cycle, resulting in the taking of a grand total from the rear totalizers, after the ordinary fashion of the Powers machine. Meanwhile, at about the middle of the second quarter turn, that is to say, at about the middle of the group total cycle, the cam 137 (Fig. 18) rocks levers 135b and 135a, shaft 134 and arm 135, pulling, by means of the link 136, the slam bail mechanism into action (Figs. 1 and 4). Also at about the middle of the third or grand total cycle, the same cam 137 again pulls the slam bail device. At the end of the third cycle, the cam 84b (Fig. 16) allows the lever 107a and the shafts 102 and 109 to resume their normal positions, permitting the card to be sensed and fed out of the chamber, and a new card to be fed in after the ordinary fashion of a tabulating cycle. Toward the end of this cycle, the cam 140 (Fig. 24) operates the clutch restoring mechanism. During all this time this mechanism, except the cam, has been in the position shown in Fig. 24, with the lever 146 tilted as shown and its end resting on the fixed stud 150a. When the follower 241 is pressed down by the cam toward the end of the fourth cycle (the first normal cycle), the downward movement of the pivot of the lever 146 gives a relative clockwise rotation of said lever, resulting in its being straightened out in alignment with the arm 143, on which it is mounted, where it is retained by the pawl 149 engaging the finger 148 (Fig. 23). When the follower 241 runs down from the high part of the cam to its normal position shown in Fig. 24, the lever 146, being rigid with the arm 143, raises the arm 151a and releases the clutch, the tension of the spring 155a (Fig. 23) completing the rotation of the cam shaft. At the end of the upward motion of the arm 143, the projecting nose of the pawl 149 striking the fixed stud 150 causes said pawl to be released from the finger 148, whereupon the lever 146 is swung by its spring to the broken or oblique position shown in Fig. 24, thus leaving the arm 151a free to descend upon the next change of grand total designation.
- The cam shafts 81 and 95a are caused to run through an extra cycle, that is to say, through the first tabulating cycle, for the following reasons. During the blank, group total and grand total cycles, the locking slides 63 (Fig. 9) are all held in inactive position, so that the set-pins which find holes in the new card, including those in the designating columns, move down and up once during each such cycle, resulting in vibration of the detecting slides 65 and 66. At the end of the grand total cycle, however, these slides 63 are released from pressure of the ball 111 by the release of the rock shaft 102 so that, when the designating pins are moved upward in the latter part of the grand total cycle, they are locked up and vibrate no more until the next change of designation. The last vibration of the

detecting slides 65 and 66, therefore, occurs in the latter part of the grand total cycle. At that time some of the followers are running down the inclines of their cams under spring pressure, and they tend to cause the cam assembly to run ahead of its drive mechanism. If, due to this cause, the clutch should be released before or during the time when a pin 68 (Fig. 9) was passing one of the noses 67, the total-taking mechanism would be tripped and cause a second total-taking operation. To assure that this could not occur would require a timing so fine that it is thought best to let the cam shaft run on for another cycle, idly except for the clutch-releasing operation.

The machine herein described is arranged to handle cards in which each vertical row of hole-positions is divided into two parts, each capable of representing a number or a letter; and this card has come to be known universally as a "ninety-column card". Each half of a vertical row is called and performs the function of a "column", and the word "column" is used in the claims in the sense indicated.

It will be noted that the described total control unit is adapted to bring about total taking by either of two different modes of operation according to the result desired, and that each of these operations involves the timed setting or "pulling" of certain parts of the machine. Thus, in the specific machine to which the invention is shown applied, and for the two kinds of results described, the following parts are "pulled" or set by the sub-total cam assembly: The hook 104 is thrown in to stop the card picker; the card stop 55 is locked down; the retract ball 11 is operated and so held; the total shaft 8 is rocked; and the slam bail device is operated. In order to secure first a sub total and then a grand total, the grand total cam assembly operates the same parts, some of them according to a somewhat different timing, and also in the third cycle rocks the grand total shaft 1. What parts are required to be "pulled" or set would vary in different tabulating machines and in different sorts of total taking operations according to the precise results desired. According to the present invention, a separate cam assembly is provided for each desired mode of total taking operation, cams being duplicated on the different assemblies where the functions are the same in both operations; and one of said assemblies connected to control a part and an operation peculiar to the mode of operation for which that assembly is designed, viz, in the present instance, the rocking of the grand total shaft 1. These assemblies are each adapted to bring about one mode of total taking operation, the assemblies being used alternatively, one for each such operation.

I claim:

1. In a punched record controlled machine, the combination of set-pins arranged in rows corresponding to the rows of index positions on the record; record-sensing devices acting to set said pins selectively according to the perforations sensed; two separate retaining devices for the set-pins of each row, said devices retaining the pins in set position until the next record is sensed, one of said retaining devices being common to some only of the pins of the row and the other to other only of the pins of the row; two separate detectors for detecting changes in the setting of the set-pins of each row, one of said detectors cooperating with the set-pins controlled by one of said retaining devices and the

other detector with the set-pins controlled by the other retaining device; and total-taking mechanism settable to be controlled by either one of said detectors, whereby total-taking may be brought about by a change of designation in one part of the row of index positions of the record without being brought about by a change in the other part of the row.

2. In a machine of the class described, the combination with record sensing mechanism, computing mechanism and printing mechanism, of a total control unit comprising a continuously driven shaft, a pair of cam assemblies, means for connecting either of said assemblies to be driven by said shaft, followers operated by the cams of said assemblies, means operated by said followers and controlling functions of the machine involved in taking totals, certain of said followers of one assembly being operatively connected to followers of the other assembly so that the same function may be controlled by either assembly and a follower controlled by a cam of one assembly and controlling a function of the machine not controlled by the other assembly.

3. In a record-controlled machine having a main drive, computing mechanism and printing mechanism, the combination of means for detecting two different changes of designation; two total-control cam assemblies, clutches, one for connecting each of said assemblies to said drive; springs for closing said clutches, one of said springs being stronger than the other; detents for holding said clutches open, each of said detents tripped by one of said detecting means; and connecting means acting when both detents are released to enable the stronger spring in closing its clutch to overcome the other spring to prevent it from closing its clutch.

4. In a card controlled tabulator, the combination with registering and recording mechanism, of set-pins arranged in rows; card controlled means for displacing said pins; bars for detecting movements of said pins, two such bars for each such row, one of said bars moved by certain of said pins and the other bar by certain other of said pins; total-taking means; and means settable at will to connect any of said detecting bars to initiate an operation of said total-taking means.

5. In a card controlled tabulating machine, the combination with registering and recording mechanism; of set-pins arranged in transverse and vertical rows; card controlled means for displacing said pins; latch-bars for retaining said pins in displaced positions, two such bars for each vertical row of pins, one bar acting on certain of said pins and the other bar on certain other of said pins; movement detecting bars for said pins, two such bars for each vertical row of pins one for detecting movement of the pin latched by one of said latch bars and the other for detecting movements of the pins latched by the other latch bar; total taking means; and means settable to cause either of said detecting bars to initiate an operation of said total taking means.

6. In a card controlled tabulating machine, the combination with registering and recording mechanism, of set-pins arranged in columns, card controlled means for displacing said pins selectively, a member universal to the pins of a column and moved by the displacement of any of said pins, a plurality of total-taking means, a plurality of members one for each total-taking means, and each when actuated initiating an

operation of its associate total-taking means, and an interponent settable to transmit the movement of said universal member to said operation initiating members selectively depending on the setting of said interponent.

5

7. In a card controlled tabulator, the combination of set-pins arranged in a series of columns, card controlled means for setting said pins, detecting bars one universal to the pins of each column and moved by said pins, two universal bars each arranged across the series of columns of pins, interponents one for each column and each settable to an inactive position and to two active positions for communicating the movement of the detecting bar of the associate column to one and the other of said universal bars, and means whereby said universal bars initiate each a special operation of the machine.

15

8. In a card controlled tabulator having registering and recording means, card feeding means and a motor drive, the combination of two cam assemblies normally idle, means for connecting said cam assemblies selectively to be driven by said motor drive during a plurality of machine cycles, means operated by a cam of the first of said assemblies for interrupting the card feed through two machine cycles, means operated by a cam of said first assembly for causing the machine to take a sub-total during the second of said two machine cycles, the second of said two cam assemblies including a cam for interrupting the card feed through three cycles and a cam for causing the machine to take a sub-total in the second of said three cycles, and means controlled by a cam of said second assembly for thereafter causing the machine to take a grand total.

20

9. In a card controlled tabulating machine, having registering and recording mechanism and a power drive, the combination of a normally idle cam assembly including a disconnecting cam, means controlled by said cam assembly for causing the machine to take a total, a clutch for connecting said cam assembly to be rotated by said power drive, means for closing said clutch, a follower spring-pressed against said disconnecting cam and moved against its spring during the rotation of said cam, said cam having a downward incline engaging said follower at near the end of the cycle of said cam assembly, and means whereby said follower when running down said incline opens said clutch, said follower serving at the same time to complete the rotation of said cam assembly.

25

10. In a computing and recording machine having a motor drive and means for accumulating totals and for taking the totals so accumulated and recording them, said means including a plurality of control elements each settable to condition the machine for the taking of a total and elements controlling functions of the machine involved in or ancillary to the taking of totals: total taking control mechanism comprising a plurality of rotatable normally inactive cam assemblies each assembly controlling at least one of said total conditioning elements and all of said assemblies containing cams connected to control operations of certain of said elements, and one of said assemblies containing a cam connected to control an operation of one of said elements not controlled by the other assembly; and means for connecting said cam assemblies to said motor drive selectively, one assembly for each total taking operation.

30

11. In a card controlled tabulator having reg-

75

istering and recording means, the combination of two total taking cam assemblies each capable of bringing about a total taking operation, mechanism controlled by said cam assemblies for taking totals said mechanism including control elements each settable to condition the machine for the taking of a total and elements controlling function of the machine involved in or ancillary to the taking of totals, each assembly controlling at least one of said total conditioning elements, both of said assemblies containing cams con-

nected to control operations of certain of said elements and one of said assemblies containing a cam connected to control an operation of one of said elements not controlled by the other assembly; a continuously rotating driving member, means for connecting said cam assemblies alternatively to be operated by said member, and means preventing simultaneous operation of the two assemblies.

WILLIAM W. LASKER. 10

CERTIFICATE OF CORRECTION.

Patent No. 2,151,406.

March 21, 1939.

WILLIAM W. LASKER, ET AL.

It is hereby certified that error appears in the printed specification of the above numbered patent requiring correction as follows: Page 2, first column, line 54, before "Mounted" insert the following sentence -

Resting upon the top of each box like element is a skeletonized intermediate frame, (Figs. 1 and 2) which is bridged at its top by the base 12 of the computing component. ;

and that the said Letters Patent should be read with this correction therein that the same may conform to the record of the case in the Patent Office.

Signed and sealed this 23rd day of January, A. D. 1940.

(Seal)

Henry Van Arsdale,
Acting Commissioner of Patents.
